(57) **CLAIM**

The ornamental design for a protective glove, as shown and described.

DESCRIPTION

FIG. 1 is an upper left view of the protective glove according to my new design showing the repeating hexagonal shaped pattern;

FIG. 2 is a front view of the protective glove shown in FIG. 1;

FIG. 3 is a rear view of the protective glove shown in FIG. 2;

FIG. 4 is a left side view of the protective glove shown in FIG. 2;

FIG. 5 is a right side view of the protective glove shown in FIG. 2;

FIG. 6 is a top view of the protective glove shown in FIG. 2; and,

FIG. 7 is a bottom view of the protective glove shown in FIG. 2.

The broken lines on the protective glove are for illustrative purposes only and forms no part of the claimed design.

1 Claim, 3 Drawing Sheets

FIG. 6

FIG. 7
